CLOCK

Walter F. Hall, Jr., Pawtucket, R. I.

Application January 25, 1955, Serial No. 34,200

Term of patent 14 years

(Cl. D42—7)

Fig. 1.

Fig. 2.

Fig. 3.

Fig. 1 is a front elevational view of a clock, showing my new design;

Fig. 2 is a top view; and

Fig. 3 is an end view of the same.

The dominant part of the design is shown in full lines.

I claim:

The ornamental design for a clock, substantially as shown and described.
